Primary Examiner — John R Yeh(57) **CLAIM**

The ornamental design for a toy floor scrubber, as shown and described.

DESCRIPTION

FIG. 1 is a perspective view of a toy floor scrubber design showing my new design.

FIG. 2 is a front view of a toy floor scrubber.

FIG. 3 is a rear view of a toy floor scrubber.

FIG. 4 is a left side view of a toy floor scrubber.

FIG. 5 is a right side view of a toy floor scrubber.

FIG. 6 is a top view of a toy floor scrubber.

FIG. 7 is a bottom view of a toy floor scrubber; and,

FIG. 8 is another perspective view of a toy floor scrubber. The broken lines throughout the drawing figures depict portions of the toy floor scrubber that form no part of the claimed design.
